UNITED STATES PATENT OFFICE.

JOHANN STUMPF, OF CHARLOTTENBURG, NEAR BERLIN, GERMANY,
ASSIGNOR TO GENERAL ELECTRIC COMPANY, A CORPORATION
OF NEW YORK.

TURBINE.

SPECIFICATION forming part of Letters Patent No. 766,293, dated August 2, 1904.

Application filed November 7, 1903. Serial No. 180,267. (No model.)

To all whom it may concern:

Be it known that I, JOHANN STUMPF, a subject of the King of Prussia, German Emperor, and a resident of 27 Rankestrasse, Charlottenburg, near Berlin, Kingdom of Prussia, German Empire, have invented certain new and useful Improvements in Steam or Gas Turbines, of which the following is an exact specification.

10. My invention relates to steam or gas turbines, and more especially to turbines with at least two turbine-wheels, which are situated so that the driving medium after passing the first turbine-wheel flows directly or under mediation of a guiding apparatus into the second turbine-wheel in which the energy of the driving medium is further utilized, the second turbine-wheel rotating in a direction opposite to the direction in which the first turbine-wheel rotates. In such turbines a third, fourth, and so on, turbine-wheel may be arranged; but it will be understood that all turbine-wheels which are situated at the side of one another rotate in opposite directions. Such turbines 25 are advantageously used for driving several screw-propellers or several dynamo-machines, ventilators, centrifugal pumps, and the like, which may be coupled in series or parallel. In all these turbines in case the turbine or any 30 part of the machines coupled to the same is damaged the whole working of the turbine must be interrupted. In order to do away with this disadvantage, I provide my new invention, which consists in providing means for holding one or several turbine-wheels fast, so that the same cannot rotate. If, for instance, in a turbine for two dynamo-machines coupled parallel, which turbine has two turbine-wheels rotating in opposite directions, each of which 35 40 turbine-wheels develops fifty per cent. of the total energy of the turbine it occurs that, for instance, by the damaging or burning of a dynamo-armature one of the dynamo-machines gets out of order, it is possible to stop the movement of that part of the turbine which drives the damaged dynamo-machine, while the other part of the turbine remains at work.

It will be understood that special means may be provided for stopping each turbine-wheel, 50 which means may be constructed in any con-

venient way so, for instance, the turbine-wheels or the shafts of the same may be held fast by means of screws, wedges, or the like or, as shown in the accompanying drawing, by arranging special wheels *a*, provided with holes *b* upon the shafts *c* and *d* of the turbine-wheels *e* and *f*, which wheels can be held fast by means of pins *g*, to be shifted into the holes *b*. The effect of the turbine-wheels which remain at work, if the movement of the other ones is stopped, is not at all changed by the stopping of the turbine-wheels. If, for instance, the primary turbine-wheel is stopped, the vanes of this turbine-wheel serve as guide-blades for the steam for the second turbine-wheels. In case of several turbine-wheels rotating alternately in one or in the opposite direction the first, third, fifth, and so on, turbine-wheels serve after stopping the movement of the same as fixed guide-blade rims for the second, fourth, and so on, turbine-wheels.

It will be clear that it is very important for nearly all factories to be able to stop only part of the driving-machine in case repairs are necessary.

Having thus fully described the nature of this invention, what I desire to secure by Letters Patent of the United States is—

1. In steam or gas turbines, the combination with two turbine-wheels rotating in opposite directions, oppositely-projecting shafts with notched devices on said shafts for preventing the movement of one turbine-wheel, while the other one rotates, substantially as described and for the purpose set forth.

2. In steam or gas turbines, the combination of several turbine-wheels rotating alternately in opposite directions, oppositely-projecting shafts and notched devices on said shafts for stopping the movement of each turbine-wheel, while the other ones rotate, substantially as described and for the purpose set forth.

In testimony whereof I have signed my name to this specification in the presence of two subscribing witnesses.

JOHANN STUMPF.
